HOLDER FOR A BUCKET

Joseph N. Amigone, Buffalo, N. Y.

Application May 16, 1955, Serial No. 36,025

Term of patent 14 years

(Cl. D58—26)

Fig. 1.

Fig. 2.

Fig. 1 is a top plan view of a holder for a bucket showing my new design; and

Fig. 2 is a view thereof in front elevation.

The broken lines appearing on the drawings are for illustrative purposes only.

I claim:

The ornamental design for a holder for a bucket, as shown and described.
